UNITED STATES PATENT OFFICE

2,642,060

OIL RANGE AND TANK

Cecil E. Chesser, Hebron, Ohio, assignor to Newark Stove Company, Newark, Ohio, a corporation of Ohio

Application December 13, 1946, Serial No. 715,991

1 Claim. (Cl. 126—44)

1

The present invention relates to domestic cooking ranges and more particularly to an improved oil supply tank and support therefor.

The principal object of my invention is the provision of an improved oil supply tank and support therefor which is safe and convenient to use and which is efficient in operation and durable in service.

Other and further objects and advantages of my invention will become apparent from the following description.

For a better understanding of the present invention and the manner in which the foregoing objects have been carried out, reference will now be had to the accompanying drawings and to the following detailed specification in both of which like reference characters designate corresponding parts throughout and in which,

Fig. 1 is a perspective view of a combination gas and oil kitchen range with the frontal door panels ajar;

Fig. 2 is a transverse sectional view through the fuel oil tank and is taken approximately on line 2—2 of Fig. 1; and

Fig. 3 is an enlarged front elevational view partially in section and is taken on approximately line 3—3 of Fig. 2.

By referring to Fig. 1 the observer will note that the combination oil and gas range herein contemplated consists essentially of a conventionally rectangular enclosure having side walls 11, each lined with sheet metal with an intermediate filling of insulation material. The back wall may be correspondingly constructed and provided with elements to join with the side walls 11 and 12, after the manner of conventional assembly methods, so that the three wall sections define an overall rectangular enclosure resting upon a supporting base 15.

The top of the range is comprised of a gas burner plate section designated 17, and an oil burner plate section designated 18, the latter of which includes the removable discs 19 and 21 which overlie the oil burner units so as to afford accessibility thereto for occasional repair, replacement, clean-out, or emergency lighting.

The front panel which is coextensive with the range width is designated 24 in Fig. 1 and in its surface may be noted the oven opening 25, the storage and fuel tank opening 26, the broiler opening 27 and the service opening 28 to the fuel oil valve apparatus. For aesthetic reasons, panel 24 is recessed slightly or in other words, is situated in a plane behind the control panel 29 which carries the gas burner control knobs 31 to 35, Fig.

2

1, the oil burner control valve drum dials 36 and 37, and the direct or starting damper control knob 38. Correspondingly, there are provided sectional door elements of a thickness corresponding to this recess or difference in plane levels, for covering each of the front panel openings, aforescribed. These include the wing doors 41 and 42, the oven door 43, and the broiler door 44 which abut each other edge to edge during closed position.

Attention will now be directed more particularly to the oil burner features of the present invention. A supply of fuel oil is carried in a cylindrical closed tank 71, Figs. 1, 2 and 3, which is supported in a horizontal position upon a sheet metal saddle structure also referred to as a sump and designated 72. The sump is a shallow open tank defined by the end walls 73 and 74 which have the curved nesting flanges 75 conform to the transverse curvature of the tank 71 and the inwardly bent side walls 76 and 77 which together form the enclosure with the bottom wall 78 for confining a quantity of fuel oil at a level such as indicated 79 in Figs. 2 and 3. The fuel within the tank 71 passes through openings 81 in a cylindrical spring housing 82 when the valve head 83 is depressed by the tank projection 84 pressing against the spring 85 and thereby leaving an escape clearance where it otherwise engages the valve seat 86 of the flange fitting 87.

As the quantity of fuel oil in the sump reservoir 72 becomes consumed and is withdrawn through the feed pipe 88, the level 79 will recede but to an extent only which will permit replacement air to enter the tank 71 through the valve seat opening. The replacement air which bubbles through the supply of fluid in tank 71 permits a portion of the fluid to flow out through the same opening and raises the level 79 to its sealing-off condition as aforescribed.

When the supply of oil in tank 71 is exhausted the tank may be removed for replenishment from its nested position on the sump 72 by rotating counter-clockwise as viewed in Fig. 3. This operation can be manipulated with the aid of the pivoted handle 89 whereupon the threaded nipple 91 together with its carried valve fittings will clear the flared curvature portion 92 especially provided for this purpose and the tank 71 may thereupon be withdrawn forwardly or towards the operator, Fig. 1. The amount of fuel supply within the tank 71 may be continuously indicated upon the float recording dial 93 which is visible when the wing door 42 is ajar. To replenish the liquid fuel in the tank 71 the screw cap or fitting 87 may

be removed by unscrewing from the nipple 91 and replenishing fuel poured into the tank 71 until filled. After this the cap 87 is restored. When the filling operation has been completed the valve head 83 urged by its spring 85 will seal the opening by seating against the valve seat curvature 86 and the tank may be reinstalled by reversing the aforescribed removal procedure, that is to say, by rotating clockwise instead of counter-clockwise until the flange fitting 87 abuts against the limit bracket 94 whereupon the head of valve 83 will then again be aligned above the embodiment 84, permitting the liquid to flow downwardly into the sump until it attains its sealing level.

The fuel oil which is supplied through pipe 88 is conveyed rearwardly of the oven, flowing gravitationally whereat it is controlled by a pair of feed supply valves preferably of the needle type which are contained within the tubular enclosures 98 and 99 that encase the needle rods 47. The upper ends of the needle rod 47 carry the aforescribed drum type dial heads 36 and 37. When the valves are opened the fluid supply from the oil reservoir will be distributed to the burners to an extent or level which corresponds with the fuel level in the sump 72.

While the present invention has been explained and described with reference to a specific embodiment it is to be understood nevertheless, that numerous modifications and variations may be incorporated without departing from the essential spirit or scope thereof. It is accordingly not intended to be limited for an understanding of the invention to the detailed disclosure in accompanying drawings, nor to the specific language in the aforesgoing description, but to be accorded instead a latitude of interpretation as afforded by the hereinto appended claim.

The invention claimed is:

In a kitchen range in which a frontal panel is provided with a rearwardly extending fluid fuel storage aperture of predetermined width dimensions, the combination with a sump tank comprising a relatively shallow horizontally disposed rectangular basin having fore and aft walls with uppermost edges formed into circular nesting flanges and inwardly converging sidewalls which

together with said fore and aft walls form a seating perimetry for a cylindrical closure cover to said sump tank, a bottom wall to said sump tank having a valve actuating protuberance with an inclined approach surface and a valve engaging abutment element, of a removable reserve liquid fuel supply storage tank of cylindrical conformity to coincide with the circular curvature of said nesting flanges and of length to overlie said fore and aft sump tank walls and thereby to constitute a closure cover to said sump tank, a protuberant valve housing jutting axially of said storage tank and located longitudinally on its cylindrical wall in a position to register with said sump tank bottom wall protuberance and abutment element, an inwardly depressible spring loaded valve head contained in said valve housing having a portion outwardly extending so as to be engaged by and depressed by said bottom wall protuberance when said storage tank is rotated while nested in said fore and aft supporting flanges, one of said sump tank side walls remote from said bottom wall abutment element being formed with an intermediate aperture in transverse registration with said bottom wall abutment so that when said storage tank is rotated in its nesting flanges said valve housing may be passed clear of said sump tank side wall.

CECIL E. CHESSER.
